UNITED STATES PATENT OFFICE

2,314,538

FLUID CONTROL APPLICATOR

Ernest L. Hollenbeck, Los Angeles, Calif.

Application August 5, 1941, Serial No. 405,503

5 Claims. (Cl. 15—138)

My invention relates to fluid control applicators of the character embodied in my copending application Ser. No. 321,621, filed March 1, 1940, now Patent No. 2,282,406, May 12, 1942.

It is a purpose of my present invention to provide a fluid control applicator which is characterized by its structural simplicity, low cost of manufacture, and the embodiment therein of a fluid feed regulator which is permanently associated with the applicator assembly in order to prevent accidental detachment and loss of the regulator.

It is also a purpose of my invention to provide a fluid control applicator having a feed duct, and ports leading to opposed surfaces of a flexible spreader tongue, for supplying fluid to such surfaces, so that as the tongue is flexed first in one direction and then the other in the manner of a paint brush, the fluid can be applied to and spread evenly over a surface to be coated.

Another purpose of my invention is the provision of a fluid control applicator embodying a fluid feed regulator which is manually operable to vary the size of the ports and to thereby control the quantity of fluid discharged from the ports.

A further purpose of my invention is the provision of a fluid control applicator which embodies a spreader tongue having a feed duct therein, flap valves flanking the tongue and controlling the discharge of fluid from the duct to the tongue, and a manually operable regulator for the valves, which is permanently associated therewith.

I will describe only two forms of fluid control applicators, and will then point out the novel features thereof in claims.

In the accompanying drawing:

Fig. 1 is a view showing in perspective one form of fluid control applicator embodying my invention.

Fig. 2 is a view showing the applicator of Fig. 1 in side elevation and with a portion thereof in section, the applicating strip being omitted.

Fig. 3 is a view similar to Fig. 2, but showing the regulator of the applicator adjusted to open the ports, as distinguished from the closed ports and corresponding adjustment of the regulator as illustrated in Fig. 2.

Fig. 4 is a transverse sectional view taken on the line 4—4 of Fig. 2.

Fig. 5 is a vertical sectional view taken on the line 5—5 of Fig. 3, and showing the applicator applied to the neck of a bottle.

Fig. 6 is a view showing in plan another form of fluid control applicator embodying my invention, with the applicating strip thereof omitted.

Fig. 7 is a view showing the applicator of Fig. 6 in side elevation and with the applicating strip applied and a portion thereof broken away.

Fig. 8 is a view showing the applicator of Fig. 7 in edge elevation, and with a portion thereof in section.

Fig. 9 is a vertical sectional view taken on the line 9—9 of Fig. 7.

Fig. 10 is a view showing the applicator of Fig. 7 in bottom plan.

Fig. 11 is a view showing the applicator of Fig. 7 inverted and applied to the neck of a bottle, a portion of the applicator tongue being in section.

Similar reference characters refer to similar parts in each of the several views.

Referring first to the form of fluid control applicator illustrated in Figs. 1 to 5, such applicator comprises, in the present instance, an elongated and tapered body 15 having a circular base 16 formed with an annular flange 17. The body 15 merges into a spreader tongue 18, which latter is likewise tapered. The elements just described constitute an integral structure or assembly which is molded from a single piece of flexible and resilient material, such as rubber.

The body 15 is formed with rounded edges 15a, 15a and flat sides 15b, 15b, the latter being formed with longitudinal extending grooves 19, the purpose of which will be described herein-after. As best shown in Figs. 2, 4, 5 the applicator assembly is molded with a feed duct 20 which extends through the base 16 and inwardly of the body 15 to a point where the latter merges into the tongue 18.

40 Two ports 21 are provided in the side 15b of the body 15, by slitting the body longitudinally and centrally for a portion of its length. These ports provide communication between the duct 20 and the sides 15b, but by reason of the resiliency of the material of which the assembly is formed, such ports are normally closed to prevent the emission of fluid from the ports.

At the upper or outer ends of the ports 21, pockets 22, 22 are provided which serve as seats 45 for a valve, as will be later described. Adjacent the pockets 22 recesses 23, 23 are formed in opposite sides of the body 15. These recesses are preferably semi-circular in form, and they serve to reduce the thickness of the rubber at the entrance ends of the ports 21 for the purpose of

facilitating movement of the valve into the ports.

As shown in Fig. 1, the spreader tongue 18 is provided at its free ends with an applicating strip 24 of fabric, or the like, the strip being secured to the tongue by a staple 25.

For opening the ports 21 and regulating the degree of opening of such ports, a fluid feed regulator is provided. This regulator is designated generally as R, and, in the present instance, comprises a yoke 26 formed of wire and substantially of rectangular configuration. This yoke has an upwardly extending portion 27, the free end of which is bent at right angles to provide a valve 28. As the regulator R is applied to the applicator assembly, the yoke 26 is extended about the body 15 so that the end portions of the yoke have frictional contact with the edges 15a for the purpose of holding the regulator in any position of adjustment along the length of the body 15. The valve 28 is extended through the pockets 22, but is movable downwardly to open the ports 21 by forcing the yoke downwardly on the body 15, as will be understood from a consideration of Figs. 2 and 3.

To associate the aforescribed applicator to a bottle or other receptacle containing a liquid such as liquid shoe dressing, I employ a metal cap C (Fig. 5) which may screw on or be otherwise secured to the neck end of the bottle. This cap is formed with an opening 29 in which is received the base 16, the flange 17 being interposed between and clamped by the cap and the bottle neck to hold the applicator in proper position on the bottle neck.

With the applicator applied to the bottle as just described and the bottle containing a liquid shoe dressing, such liquid may be applied to the surface of a shoe by manipulating the bottle and applicator as follows: By inverting the bottle and applicator and using the former as a handle, the applicating strip may be worked back and forth over the shoe surface in the manner of a paint brush, the tongue 18 being flexed first in one direction and then the other.

To permit discharge of the liquid the ports 21 are opened by forcing the regulator R inwardly on the body 15, or from the position shown in Fig. 2 to that shown in Fig. 3. Under such movement of the regulator the valve 28 passes from the pockets 22 inwardly of the slits to spread the latter and thus open the ports. With opening of the ports the liquid is free to flow from the duct 29 outwardly of the ports 21 to opposed surfaces of the tongue 18, and finally to the applicating strip 24. Thus, by repeated oscillation of the tongue 18 the liquid, as fed to the applicating strip, can be applied to the surface of the shoe. The grooves 19 serve to prevent the liquid from flowing off of the edges of the body 15, and to direct liquid toward the applicating strip.

Manifestly, through manipulation of the yoke 26, the valve 28 can be adjusted lengthwise of the ports to vary the degree of opening of the latter, and thereby regulate the flow of liquid to a nicety and in keeping with the particular requirement. However, once the valve is returned to the pockets 22 the ports close to prevent further emission of liquid.

Referring to the second form of fluid control applicator as illustrated in Figs. 6 to 11 inclusive, here again the applicator assembly is a unitary structure of rubber or other suitably resilient and flexible material. This assembly comprises a body 30 having an annular flange 31, a spreader tongue 32 which is tapered but flat to present

opposed surfaces 32a, 32a, and a pair of tapered flap valves 33 flanking the tongue.

5 Interiorly the body 30 is formed with a fluid feed duct 34 which is tapered, as shown in dash lines in Fig. 7. The valves 33 are formed by splitting the body 30 longitudinally at opposite sides of the tongue, and in order that these valves may remain attached to the body, the splits terminate short of the bottom of the body.

10 As in the first form of my invention, the tongue 32 carries an applicating strip 35 of suitable fabric, but in this instance the strip is cemented or glued, to the tongue. To facilitate such cementing, the tongue at its sides 32a is provided with grooves 36 which form channels in which the cement is received, thereby providing a more secure bond between the tongue and strip.

15 The grooves 36 may extend the entire length of the tongue, in which case those portions of the 20 grooves to the sides of the valves 33, function to prevent the liquid as emitted from the duct, from flowing to and off the edges of the tongue. The grooves also direct the flow of fluid to the applicating strip 35, and augment the flexibility of the tongue.

25 For regulating the quantity of liquid emitted from the duct 34, a regulator R' is provided. This regulator is made of relatively light and resilient wire, and comprises a U-shaped yoke 37 having 30 its free ends bent to form a pair of confronting trunnions 38 rotatably seated in recesses 39 of the valves 33 (Fig. 8). Protuberances 40, 40 in the shape of beads are formed on the outer sides of the valves 33 to be embraced by the parallel portions of the yoke 37, and by virtue of their resiliency to frictionally retain the regulator R' in any position to which it can be swung.

35 As in the first form of my invention, the present applicator is adapted to be mounted on the neck N (Fig. 11) of a bottle or other receptacle containing a liquid such as shoe dressing. For this purpose a cap C' similar to the cap C is employed to embrace the flange 31 and securely hold the applicator in proper position on the bottle neck.

40 In the use of my applicator, the regulator R' first is swung to the broken line position shown in Fig. 7, whereupon by using the bottle as a handle the applicating fabric 35 is worked back and forth over the surface of the shoe. Normally, the valves 50 33 lie in close contact with opposite sides of the tongue 18 so that opposite sides of the outer end of the duct 34 are closed. However, with the valves free and the tongue 18 subjected to a back and forth motion, the latter is flexed first in one direction and then the other to such an extent that first one valve and then the other is so flexed as to leave the unflexed valve spread away from the adjacent face of the tongue. This allows 55 liquid to flow from the duct 34 first to one side 32a of the tongue and then the other, and from there to the applicating fabric 35, thereby constantly supplying liquid to the applicating fabric.

60 When the regulator R' is in the solid line position shown in Fig. 7, the outer ends of the protuberances 40 are engaged by the yoke 37, to secure the flap valves 33 against flexing even when the tongue 18 is flexed, so that there can be no escape of liquid. However, when the regulator is adjusted toward the broken line position shown in Fig. 7, the flap valves may be flexed to a degree which increases with such adjustment. As 65 the degree to which the valves may be flexed controls the quantity of flow of fluid from the duct,

it will be clear that the quantity flow is directly controllable by adjustment of the regulator.

In practical use of the applicator and bottle, the regulator R' normally occupies the position shown in solid lines in Fig. 7, wherein the valves 33 are engaged by the yoke to prevent such flexing of the tongue 18 and the valves as would cause the valves to open and allow liquid to be discharged from the duct 34. However, upon moving the regulator to the broken line position shown in Fig. 7, or any position intermediate this and the position shown in solid lines, the valves are partially or fully released to permit them to flex under flexing movements of the tongue.

I claim:

1. In a fluid control applicator, a body of resilient material, a tongue of resilient and flexible material, a duct in said body, ports in said body leading from said duct to points exteriorly of said body and urged to closed position, a valve for adjustably opening said ports, and means frictionally engaging said body for retaining said valve in any position of adjustment.

2. In a fluid control applicator, a body of resilient material having a duct therein and ports leading from said duct to opposed surfaces of said body, said ports urged to closed position, a flexible tongue on said body, and a manually operable regulator for said ports, comprising a valve,

and a member secured to the valve and adjustable on said body for actuating and holding said valve in adjusted positions in respect to said ports.

- 5 3. In a fluid control applicator, a body of resilient material having a duct therein and ports leading from said duct to opposed surfaces of said body, said ports urged to closed position, a flexible tongue on said body, and a manually operable regulator for said ports, comprising a yoke adjustable on said body but frictionally held in adjusted positions thereon, and a valve fixed to said yoke so as to be movable therewith to occupy corresponding positions of adjustment.
- 10 4. In a fluid control applicator, a body of resilient material having a duct therein and slit to form ports leading to said duct but urged to closed position, a flexible tongue on said body, pockets at one end of said ports, a valve normally seated in said pockets, and a member to which said valve is secured, said member frictionally embracing said body so as to be adjustable thereon for moving said valve from said pockets into and opening said ports.
- 15 5. In a fluid control applicator as embodied in claim 4, wherein the material about said pockets is relatively thin to facilitate movement of said valve out of the pockets into said ducts.

ERNEST L. HOLLENBECK.
